UNITED STATES PATENT OFFICE.

MINOR W. FELVEE AND RAYMOND A. JOHNSON, OF DELANO, CALIFORNIA.

COIN-CONTROLLED LIQUID DISPENSER.

Application filed April 27, 1927. Serial No. 186,882.

This invention relates to coin control liquid dispensing devices and particularly represents improvements over and modifications of the type of apparatus shown in our co-pending application for patent, Serial No. 154,682, filed December 14th, 1926. In the previous device the liquid was dispensed from the pump cylinder by hand, the hand control means being able to function only after a coin had been deposited in its corresponding slot and a lever depressed. The present invention does away with the hand operation of the pump and contemplates the use of one whose strokes are governed by compressed air working against the piston of an air cylinder attached to the plunger rod of the pump.

The principal object of the present invention is to provide a control apparatus arranged in connection with an air operated pump of the above general type, so constructed that after a coin has been deposited and the control lever has been pressed, the air valve in the air line to the cylinder will be automatically opened; and when the pump plunger has moved to dispense an amount of liquid equal in value to that of the coin deposited, said valve will be automatically closed. At the same time another valve to admit air to the opposite end of the cylinder will be automatically opened. When the pump plunger has returned to its normal lowered position the last named air valve will be again automatically closed, while the other valve will still remain closed and in a position ready to be again opened upon a further movement of the coin controlled lever. This apparatus therefore is much more convenient and simpler for a customer to operate since it eliminates all hand operations except the depositing of the necessary coin and a slight movement of a single easily manipulated control lever.

These objects we accomplish by means of such structure and relative arrangement of parts as will fully appear by a perusal of the following specification and claims.

In the drawings similar characters of reference indicate corresponding parts in the several views:

Fig. 1 is a sectional elevation of our improved apparatus showing the parts in their normal positions or with the pump plunger rod fully retracted and ready for a dispensing movement.

Fig. 2 is an enlarged end view of the air valves and their control means, the parts being in the same position as in Fig. 1.

Fig. 3 is a top plan view of the parts of the structure shown in Fig. 2.

Fig. 4 is an enlarged end view of the air valves and their control means with the parts in the positions occupied just after the depression of the coin controlled lever.

Fig. 5 is a similar view with the parts in the positions occupied when the pump plunger rod has been raised to its limit of movement as determined by the selective stop and has caused the dispensing control valve to be closed and the other or return move- 70 ment valve to be opened.

Fig. 6 is a fragmentary plan of the coin controlled lever and the plunger-rod stop mechanism associated therewith, taken substantially on the line 6—6 of Fig. 1.

Fig. 7 is a fragmentary outside elevation of the upper end of the casing containing the coin controlled mechanism.

Referring now more particularly to the characters of reference on the drawings, the 80 numeral 1 denotes the barrel or cylinder of an ordinary vertical gasoline pump, from which the plunger rod 2 projects upwardly. Attached to the upper end of this rod is a piston 3 working in a vertical air cylinder 85 4, said piston having a stroke the same length as that of the pump plunger.

Extending between the pump and the air cylinder and parallel to the rod 2 is a turnable shaft 5 from which, at vertically spaced 90 intervals, fixed stops 6 project radially in circumferentially spaced relation to each other. One at a time of these stops is adapted to project into the path of movement of a fixed stop 7 projecting from the plunger rod 2. The 95 shaft 5 also has another stop 8 below the stops 6 and arranged to be engaged by the rod stop 7, which is disposed between said stops 6 and 8.

Mounted in fixed relation to the pump and its associated parts are horizontally disposed air valves comprising cylindrical casings 9 and 10, with rotors 11 and 12 turnable therein. The valves are disposed on opposite sides of the shaft 5 above the stop 8. Air intake 100 openings or passages 13 in the casings are adapted for connection to a source of compressed air, such as is at present available in all service or filling stations of any size. An air pipe 14 leads from the casing 9 in cir- 110

5 circumferentially spaced relation to the intake opening to the bottom of the air cylinder 4; while a pipe 15 leads from the casing 10 in circumferentially spaced relation to the air intake thereof to the top of the cylinder. The rotor 11 has a passage 16 to establish communication between the opening 13 and the passage 14; while the rotor 12 has a similar passage 17 to establish communication between the corresponding intake 13 and the pipe 15. The rotors also have additional passages 18 and 19, respectively, offset from the passages 16 and 17, to establish communication between the pipes 14 and 15, respectively, and exhaust openings 20 in the casings. Such communication of course is only arranged to take place when the passages 16 and 17 are out of register with the pipes 14 and 15.

20 Radial arms 21 and 21^a project in a substantially horizontal direction and toward each other from the rotors 11 and 12, respectively, said arms being connected at their outer ends to links 22 and 22^a. The lower ends of these links are connected to vertical bars 23 and 23^a, respectively, which are slideable in guides 24 mounted in fixed connection with the valve supporting members 25. The lower ends of the bars have lugs or feet 26 and 26^a, respectively, projecting therefrom, the foot 26 projecting into the path of movement of the stop 8 and the foot 26^a projecting into the path of movement of the stop 7 as well as the stop 8. The valve rotors are so arranged that when the bar 23 is raised the exhaust of the valve 9 is open and the air flow to the cylinder 4 is shut off; while when the bar 23^a is down the exhaust of the valve 10 is open and the air flow to the cylinder 4 is shut off. When the position of the bars is reversed the positions of the valve rotors is reversed also. In other words the opening movement of these valves takes place with opposite movements of the bars. The normal position of the bar 23 is up so that the valve 9 is closed and the normal position of the bar 23^a is down so that the valve 10 is also closed. By "normal position" is meant the position occupied after the cycle of dispensing operations has been completed and the parts of the structure are ready for further dispensing operations. It will therefore be seen that if the bar 23 is lowered from said normal position the valve 9 will be opened, as shown in Fig. 4, and the air will flow to the bottom of the air cylinder to act on the piston therein and raise the same. The plunger rod of the pump will also be raised and the liquid dispensed from the pump. When the stop 7 on the plunger rod reaches whichever one of the stops 6 has been moved by rotation of the shaft 5 to be in the path of said stop 7 said shaft will be raised. The stop 8 will be raised also and bearing against the feet 26 and 26^a of both valve-connected bars will

raise both said bars. This results in the valve rotors being turned; the valve 9 to an air feed closing position and an exhaust opening position; and the valve 10 to an air feed opening position and exhaust closing position 70 as shown in Fig. 5.

In order to insure the continued turning of each rotor to its exhaust opening position even after the air to the cylinder has been shut off (or vice versa), and the movement 75 of the plunger rod has been consequently halted, the links have slotted connection with the arms 21 and 21^a, and snap action springs 27 are applied to said arms to throw them in one direction or the other to complete the 80 movement of the rotors to the necessary extent, whether the bars are being moved up or down.

The valves having been moved to the above described positions air enters the top of the 85 cylinder while it exhausts from the lower end, and the pump plunger rod is forced down to its lowermost position, the pump cylinder refilling with liquid during such movement, as is customary. With the approach of the 90 plunger rod to such position, the stop 7 will engage the foot 26^a and press the same down to effect the closing of the valve 10. At the same time such movement causes the stop 8 to be lowered to its original position also, since 95 the foot 26^a is still engaged with said stop. The valve 9 will still remain closed however since the foot 26 controlling said valve is not engaged by the stop 7. The bars and the valves controlled thereby are thus returned 100 to the original positions shown in Fig. 2 and the pump will remain idle until the valve 9 is again moved to its open position by the necessary rotation of its rotor.

Rotation of the rotor for the above purpose, 105 and the rotation of the shaft 5 to selectively place any stop 6 into the path of movement of the plunger rod stop 7 is performed by the following structure:

Mounted in connection with the pump to 110 one side of the same is a vertical and preferably cylindrical casing 28, disposed so that the shaft 5 is between the plunger rod and the casing. Turnable in the casing is a vertical shaft 29 from the upper end of which a 115 lever 30 projects a certain distance outwardly of the casing. The lever is pivotally connected to the shaft so as to have vertical swinging movement relative thereto, while causing the shaft to be rotated when the lever 120 is turned horizontally. The lever passes through a circumferential slot 31 in the casing, vertical and spaced slots 32 being disposed below and communicating with the slot 31 to receive the lever 30 therein when said 125 lever is depressed. Below the slots 32, coin openings 33 of different sizes, to receive different coins, are cut through the front of the casing. (See Fig. 7.) Three coin openings are preferably provided to receive 25¢, 50¢ 130

and \$1.00 coins and there is a corresponding number of stops 6 on the shaft 5.

Fixed on the shaft 29 intermediate its ends is a radial arm 34 disposed in horizontal alignment with and parallel to a similar arm 35 fixed on the shaft 5. A link rod 36 connects the arms. It will therefore be seen that upon moving the lever along the slot 31 the shaft 5 will be rotated and the position of the stops 6 relative to the plunger rod stop will be altered accordingly. The stops 6 are set relative to the slots 32 so that when the lever is vertically aligned with the different slots the stops in their respective order will be turned to be engaged by the stop 7. The stop 6 corresponding to the smallest coin opening is of course the lowest one on the shaft, the others being correspondingly disposed and all being located on the shaft so as to permit an upward and dispensing movement of the pump plunger corresponding to the value of the coin deposited in the machine.

A coin actuated mechanism arranged in connection with each coin opening and of any suitable nature or such as is shown in our co-pending application for patent above mentioned prevents the lever from being fully depressed in any slot 32 until a coin of the proper value has been inserted in the corresponding opening 33. The depression of the lever causes the valve 9 to be opened and held open until the pump plunger has completed the portion of its stroke corresponding to the value of the coin deposited by the following structure:

The lever when aligned with any of the slots 32 is adapted to bear down on a horizontal arm member 37 pivoted in the casing 28 under said lever. Attached to the arm is a vertical bar 38 which at its lower end is pivoted in connection with another horizontal arm 39 pivoted at one end in the casing. The free end of the arm 39 carries an upwardly projecting pin 40 which is slidable through a fixed guide 41. This pin is adapted to engage a recess or notch 42 cut in a transverse shaft 43 fixed in the casing. A spring 44 acts to normally hold the pin in such engagement. The stem 45 of the valve rotor 11 projects into the casing and carries on its inner end a radial arm 46 which passes under the arm 39 at right angles to the longitudinal plane thereof, as shown in Fig. 1. The free end of this arm when the valve is in its closed position is immediately adjacent the arm 39. It will therefore be seen that when the lever 30 is depressed the arm 39 will be depressed likewise, withdrawing the pin 40 from the recess 42 and depressing the arm 46 so as to rotate the stem 45 and turn the valve rotor toward an open or air feeding position. As soon as the rotor has been turned past the dead-center position of the snap action spring 27 of the valve, the spring functions to complete the movement of the rotor and the arm

46 will be lowered clear of the arm 39. The pump will be then put into operation as previously described.

Slidable on the shaft 43 is a sleeve 47 normally pressed against the pin 40 by a spring 48. As soon as the pin is released from the notch 42 by depression of the lever 30, the spring 48 functions to move the sleeve along so as to cover the notch and thus prevent return of the pin into place. The member 37 is then held from rising and the lever 30 is likewise held depressed in its slot 32, since the member 37 is provided with a longitudinal slotted guide member 49 through which the lever travels and which holds said lever in close vertical association therewith.

When the sleeve 47 is thus released, a lug 50 depending therefrom bears against stops 51 mounted on a rod 52. This rod projects through to the outside of the casing and is connected to one arm of a bellcrank 53, the other arm of which engages a grooved collar 54 on the shaft 5. Therefore when the shaft is raised by engagement of the plunger rod stop 7 with the stop 6 of said shaft, said collar will be raised and the bellcrank will be turned so as to force the stops 51 against the lug 50, moving the sleeve 47 against the pressure of the spring 48 and causing said sleeve to clear the notch 42. The pin 40 will then reenter said notch owing to the pull of the spring 44 thereon and the arm 39 and the parts connected thereto will return to their normal raised positions.

Though we have shown an air valve controlling the admission of air to the upper end of the cylinder, as well as to the lower end thereof, such upper end air valve may be omitted if it is desired to use gravity for the return movement of the pump plunger.

A yieldable spring-pressed catch structure C is associated with the shaft 5, in order to maintain it set in position when shifted by the movement of the plunger-rod.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention what we claim as new and useful and desire to secure by Letters Patent is:

1. A liquid dispensing apparatus including a dispensing pump-cylinder, a plunger-operating rod projecting therefrom, an air cylinder, a piston movable in the air cylinder and connected to the rod, air passage means to the air cylinder to enable air to be fed against the piston to move said piston and the rod in a dispensing direction, an air valve

in said passage means, hand controlled means for opening the valve, and automatically functioning means for causing the valve to be closed after the rod has moved a predetermined distance in said dispensing direction.

2. A liquid dispensing apparatus including a dispensing pump-cylinder, a plunger-operating rod projecting therefrom, an air cylinder, a piston movable in the air cylinder and connected to the rod, air passage means to the air cylinder to enable air to be fed against the piston to move said piston and the rod in a dispensing direction, an air valve in said passage means, hand controlled means for opening the valve, and means actuated by the movement of the rod a predetermined distance for then automatically closing the valve.

20 3. A liquid dispensing apparatus including a dispensing pump-cylinder, a plunger-operating rod projecting therefrom, an air cylinder, a piston movable in the air cylinder and connected to the rod, air passage means to the air cylinder to enable air to be fed against the piston to move said piston and the rod in a dispensing direction, an air valve in said passage means, a hand operated lever movable in two distinct directions, means between the lever and valve for opening the latter with a movement of the lever in one direction, means actuated by the movement of the rod a predetermined distance for closing the valve, and means controlled by a movement of the lever in the other direction for determining the extent to which the rod may thus move.

4. A liquid dispensing apparatus including a dispensing pump-cylinder, a plunger-operating rod projecting therefrom, an air cylinder, a piston movable in the air cylinder and connected to the rod, separate air passages leading to the opposite ends of the air cylinder, valves in said passages, both said valves being normally closed, hand operated means for opening one valve, and means actuated by the movement of the plunger rod a predetermined distance for closing said one valve and opening the other valve.

5. A liquid dispensing apparatus including a dispensing pump-cylinder, a plunger-operating rod projecting therefrom, an air cylinder, a piston movable in the air cylinder and connected to the rod, separate air passages leading to the opposite ends of the air cylinder, valves in said passages, both said valves being normally closed, hand operated means for opening one valve, means actuated by the movement of the plunger rod a predetermined distance for closing said one valve and opening the other valve, whereby to reverse the direction of flow of air to the cylinder and cause the rod to be moved in the opposite direction, and means governed by the movement of the rod to the end of its stroke,

in said opposite direction for then closing said other valve without again opening said one valve.

6. A liquid dispensing apparatus including a dispensing pump-cylinder, a plunger-operating rod projecting therefrom, an air cylinder, a piston movable in the air cylinder and connected to the rod, an air valve comprising a body and a valve rotor therein, an air intake passage to the body, an air delivery passage from the body leading to the cylinder, an exhaust opening in the body, and a valve element in the body to establish communication between the intake and delivery passages and between the delivery passage and the exhaust opening respectively and alternately, a vertical bar connected to and depending from the valve, a laterally projecting foot on the bar, a vertically movable shaft disposed parallel to the plunger rod, a stop on the shaft under the foot, said foot when the valve is closed being raised from the stop when the shaft is in its normal position, hand means for moving the valve to an open position and for causing the foot to then lie immediately adjacent and over the stop, and means governed by the outward movement of the plunger rod a predetermined distance for raising the shaft and causing the stop to raise the foot and move the valve to a closed position.

7. A liquid dispensing apparatus including a dispensing pump-cylinder, a plunger-operating rod projecting therefrom, an air cylinder, a piston movable in the air cylinder and connected to the rod, an air valve comprising a body, an air intake passage to the body, an air delivery passage from the body leading to the cylinder, an exhaust opening in the body, and a movable element in the body to establish communication between the intake and delivery passages and between the delivery passage and the exhaust opening respectively and alternately, a vertical bar connected to and depending from the valve, a laterally projecting foot on the bar, a vertically movable shaft disposed parallel to the plunger rod, a stop on the shaft under the foot, said foot when the valve is closed being raised from the stop when the shaft is in its normal position, hand means for moving the valve to an open position and for causing the foot to then lie immediately adjacent and over the stop, a stop projecting from the plunger rod, and a stop projecting from the shaft, said rod stop being disposed between said shaft stops and the latter being both in the path of movement of the rod stop.

8. A liquid dispensing apparatus including a dispensing pump-cylinder, a plunger-operating rod projecting therefrom, an air cylinder, a piston movable in the air cylinder and connected to the rod, separate air passages leading to the opposite ends of the air cylinder, valves in said passages, said valves in

cluding movable elements both normally closed, bars depending from and connected to the elements, feet projecting laterally from the bars, the bar and foot of one valve being raised relative to the other valve when both valves are closed, and being arranged to open by movements in opposite directions, a vertically movable shaft disposed parallel to the plunger rod, a stop on said shaft under the feet to engage both the same, hand means applied to said one valve to open the same and lower the corresponding foot to a level with the other foot, another stop on the shaft above the feet, and a stop on the plunger rod 10 between the feet and said other shaft stop and arranged to engage the same and raise the shaft after the rod has been raised a predetermined distance with the opening of said one valve; the shaft stop being positioned, 15 upon the retractive movement of the plunger rod, to engage and lower the foot of the bar connected to said other valve but not the foot of the bar connected to the hand-opened valve. 20

9. A liquid dispensing apparatus including a dispensing pump-cylinder, a plunger operating rod projecting therefrom, an air cylinder, a piston movable in the air cylinder and connected to the rod, separate air passages leading to the opposite ends of the air cylinder, valves in said passages, said valves including movable elements both normally closed, bars depending from and connected to

the elements, feet projecting laterally from the bars, the bar and foot of one valve being raised relative to the other valve when both valves are closed, and being arranged to open by movements in opposite directions, hand means applied to said one valve to open the same and lower the corresponding foot to a level with the other foot, and means actuated by the outward movement of the plunger rod after said one valve has been opened and the rod has moved a predetermined distance for raising both feet to close the one valve and open the other, whereby movement will be imparted to the plunger rod in the opposite direction, and for then lowering the foot connected to said other valve to lower and again close the same by the time the plunger rod has moved to a fully retracted position, without imparting any movement to the foot connected to said one valve to alter the already closed position of the same. 30

10. A structure as in claim 4 with snap action means incorporated with said last named means to cause the valves to be suddenly moved with a rapidity in excess of that of the movement of the plunger after said plunger actuated means has functioned to a predetermined extent.
